UNITED STATES PATENT OFFICE.

SQUIRE FRANKLIN DU REE, OF LONGBEACH, CALIFORNIA.

TRAFFIC-LANTERN.

1,084,411.

Specification of Letters Patent. Patented Jan. 13, 1914.

Application filed April 1, 1913. Serial No. 758,115.

To all whom it may concern:

Be it known that I, SQUIRE F. DU REE, a citizen of the United States, and a resident of Longbeach, in the county of Los Angeles and State of California, have made certain new and useful Improvements in Traffic-Lanterns, of which the following is a specification.

My present invention relates to traffic lanterns, and more particularly to a lamp box adapted to contain a light provided with transparent portions whereby to eliminate all danger in traffic by an obstruction in darkness.

A further object of my invention is to provide a lamp box which will indicate the direction in which all traffic should turn and also indicating the care which should be observed in passing by the obstruction.

A still further object of my invention is to provide a lamp box at least one side of which is removable and reversible whereby both sides of the box may be made to indicate the same direction for traffic or opposite directions as desired.

In the accompanying drawings which illustrate my invention, Figure 1 is a side elevation of one side of the lamp box. Fig. 2 is a similar view partly in section to show the interior of the box. Fig. 3 is an end elevation. Fig. 4 is a similar view partly in section. Fig. 5 is an elevation of the removable side detached, and Fig. 6 is a detail horizontal section taken substantially on the line 6-6 of Fig. 5.

Referring now to these figures, A indicates a substantially rectangular lamp box, the base a of which is provided with an intermediate depression a' whereby to receive the base of a light giving lamp as indicated in dotted lines at B in Fig. 2, and the ends C of which are provided with diamond-shaped transparent sections e in order to attract attention to the traffic lantern of those approaching an obstruction in a direction at right angles to the line of traffic.

One of the sides D is permanently formed while the other side D' is removably disposed in longitudinal guides a² formed on a lamp box. Each of these sides is provided with a longitudinal arrow shaped transparent section d, and has a rotatable disk E disposed against its inner surface and pivoted on a stud e which extends through the side as particularly shown in Fig. 6, and is provided with an exterior handle e' by

which the disk E may be rotated from the outside of the lamp box. Each disk E is provided with a plurality of transparent sections e², e³ and e⁴, disposed in a series around the pivot e and adapted to be brought into alinement with an opening d' in the respective box side by rotation of the handle e', the latter being provided with a similar pin e⁵ adapted to enter one of a series of apertures d² in the respective box side in order to maintain the disk E in selected position.

The several transparent sections above mentioned are formed by means of openings over which are suitably fastened transparent material, either fabric or glass or in fact any material which is adapted to be colored and to serve the purpose. The transparent sections c of the box ends C are red as indicated and the arrow shaped transparent sections d of the sides D and D' are similarly colored, while the transparent sections of the disks are various colors, the section e² being red, the section e³ being yellow, and the section e⁴ being green.

In its use the lamp box is to be placed upon an obstruction with the arrow shaped transparent sections d pointing to the direction in which the traffic is to pass the obstruction and it will thus be seen that in view of the fact that the side D' is removable and may thus be readily reversed, the arrow shaped transparent sections upon opposite sides of the box may either point in the same or relatively opposite directions.

Further indications are then given by means of the revolvable disks E which, upon being rotated to show a red light, indicate "no passage." Upon being turned to show the yellow light, indicate "caution" and upon being turned to show the green light, indicate "clear passage." Thus if traffic is entirely closed by the obstruction, the transparent sections e² are turned in alinement with the apertures d' at each side of the lamp box, while if there is a passage on only one side of the obstruction, the transparent sections e³ are turned to aline with the side openings d' at each side of the lamp box, the removable side D' being so disposed that its arrow shaped transparent sections d' point in the same direction as that of the side D. Thus notice is given that traffic in opposite direction can pass on only one side of the obstruction and should therefore proceed with caution. Similarly where there is passage

upon both sides of the obstruction, the side D' is reversed so that its arrow points in a direction opposite to that of the arrow of the side D, the transparent section e⁴ of the 5 disk E being turned to register with the side opening d' at each side of the lamp box, thus showing a green light to indicate a clear passage and also designating the side of the obstruction upon which traffic is to 10 turn when approaching the same from opposite directions.

It will be further understood that I may vary to some extent the details of construction which I have shown and thus fully described, for instance by providing a series of 15 depressions a' in the base a of the lamp box whereby to accommodate a series of lamps. This change and various other changes and modifications may be made without departing from the spirit and scope of the invention as outlined in the appended claims.

I claim:

1. A lamp box having a permanent side and a removable and reversible side, each of 25 which sides is provided with an arrow shaped transparent colored section and with an aperture alined with the point of the said transparent section, a disk rotatable upon the inner surface of each of the said sides and provided with a plurality of transparent 30 sections of different colors, a stud upon which the disk is mounted whereby the same may be rotated to bring a selected colored section thereof in alinement with the open-

ing of the respective box side, means having 35 connection with the stud whereby to rotate the disk, and a lamp within the lamp box, all for the purpose described.

2. A traffic lantern comprising a casing or box, the opposite sides of which are provided 40 with transparent colored sections constituting direction indicators, and which are also provided with openings adjacent said direction indicators, and multi-colored indicators movable on the said sides of the casing or 45 box whereby they may be selectively alined with the openings of the box sides, one of said box sides being removably and reversibly disposed in connection with the casing or box, all for the purpose described. 50

3. A traffic lantern embodying a box or casing having opposite sides thereof provided with transparent sections forming permanent indicators, and a disk rotatably mounted on each of the said box sides adjacent to the permanent indicators and having multi-colored transparent sections, the box sides being provided with apertures with which each of the transparent sections of the disks may be brought into alinement, means 60 for rotating the disks, and one of said box sides being removably and reversibly disposed in connection with the casing or box, all for the purpose described.

SQUIRE FRANKLIN DU REE.
